CLAIM

The ornamental design for an educational poster, as shown and described.

DESCRIPTION

The patent or application file contains at least one drawing executed in color. Copies of this patent or patent application publication with color drawing(s) will be provided by the Office upon request and payment of the necessary fee. The sole drawing FIGURE is a front elevational view of the educational poster. The design of the educational poster is printed on flat material.

1 Claim, 1 Drawing Sheet
